UNITED STATES PATENT OFFICE.

EDMOND PICARD, OF PARIS, FRANCE.

VARIABLE CONDENSER WITH SMALL LOSS.

Application filed June 19, 1925, Serial No. 38,254, and in France June 3, 1925.

The present invention relates to a variable condenser adapted for use with high frequency circuits, and which is specially constructed with a view to obtaining a high insulation and to reducing to a minimum the residual capacity, the loss by dielectric hysteresis, and other prejudicial effects.

In the said variable condenser, the movable element or rotor is maintained between two metallic cheeks or end plates which are in parallel disposition and are connected together by suitable posts or uprights. The stationary element or stator is supported by two cross-pieces, made of insulating material, which are secured to the said uprights by suitable connecting members.

I prefer to construct the said cross-pieces in the form of rods made of melted quartz or silica, and suitable straps may be attached to their ends for connecting them to the frame of the instrument.

To provide for the suitable mounting of the said condenser elements with reference to one another, and for the proper assembling of the various parts of the instrument without the occurrence of prejudicial internal effects, certain of the holes for the screws attaching the several parts are elongated, thereby offering a certain latitude for the adjustment.

The appended drawing shows by way of example a perspective view of one embodiment of my said invention.

The rotor and stator elements or members of the said variable condenser consist, in the known manner, of metallic plates which are superposed with a uniform spacing. The rotor 1 is mounted on the shaft 2 which is supported by two parallel metallic plates 3 and 4 which are connected together by the posts 5.

The plates forming the stator 6 are connected at each side, by soldering or like means, with a metallic block 7 which is supported through the medium of a connecting member or strap 8 by an insulating cross-piece 9 secured to the two adjacent posts by connecting straps 10 analogous to the member 8.

The two cross-rods 9 supporting the stator 6 consists preferably of melted quartz or silica, this being an insulating material which possesses the maximum qualities with reference to high frequency currents.

In addition to a very considerable resistivity, quartz possesses the known property

of reducing to a minimum the residual capacity, the loss by dielectric hysteresis and other prejudicial effects.

At each end of the cross-rods 9, I preferably secure a connecting strap or member 11 for attaching the instrument to a suitable support. Each member 11 consists of two parts which are screwed together and which form at one end an apertured angle piece 12 and at the other a collar 13 which fits upon the cross-piece 9. The height of the members 11 is such that the plane of the four angle pieces 12 is situated above the upper plate 3, so that when the instrument is secured to a panel or other flat member by means of the said cross-pieces 9, none of the metallic parts connected with the stator will be in contact with the said flat member.

The condenser according to the invention is thus mounted after the manner of the known condensers, i. e. the shaft 2 of the rotor traverses, without contact, the panel to which the instrument is secured; on the outer end of the said shaft is disposed a control knob 18 provided with a graduated dial.

The terminals for the current may be respectively disposed on one of the blocks 7, for the stator, and on the shaft 2 by means of a soldered flexible wire, for the rotor.

To facilitate the assembling of the parts and the adjustment of the relative positions of the two main elements 1 and 6, the connecting members or straps 8 and 10 are secured respectively to the block 7 and to the posts 5 by screws 14 passing through slots 15 in said connecting members.

Certain of the posts 5 are secured to the end plates 3 and 4 by screws 16 passing through slots 17 in the said plates.

In this manner I mount the said instrument by first screwing tightly all the screws which have no play in their apertures, and then by screwing all the screws passing through slots, so that there will be set up no internal stresses which would be prejudicial to the substantial construction of the instrument.

I regulate the stationary element 6 relatively to the movable element 1, by displacing the latter by sliding it upon the cross-pieces 9 and by moving each block 7 relatively to the connecting member 8; this motion may take place by reason of the slots 15 in the said connecting member.

Obviously, the condenser of the simple type which has been hereinbefore set forth is given solely by way of example, and it is susceptible of all desired improvements such as are usually made in this class of instrument, i. e. slow movement of the rotor, devices for taking up the play, and the like, without departing from the principle of the invention.

10 I claim as my invention:

1. A variable condenser, comprising a frame consisting of a pair of spaced cheek plates, and a plurality of posts connecting the same; a pair of cross-rods carried by said posts and constructed of silicious insulating material; a metal block carried by each rod; a set of stator plates carried jointly by said blocks; a set of rotor plates for cooperation with the stator plates; a shaft 15 to which the rotor plates are attached journaled in said cheek plates; an operating member attached to said shaft; and fastening straps secured to the ends of said rods for attaching the instrument to a supporting panel.

2. A variable condenser, comprising a frame; a pair of oppositely-located cross-rods attached to the frame and constructed of silicious insulating material; a set of 20 stator plates carried jointly by said rods; a rotor mounted in said frame and embody-

ing a set of plates for cooperation with the stator plates; and fastening straps secured to the ends of said rods for attaching the instrument to a supporting panel.

3. A variable condenser, comprising a frame consisting of a pair of spaced cheek plates, and a plurality of posts connecting the same; a pair of oppositely-located cross-rods made of silicious insulating material; 40 a set of supporting straps for said rods having screw-and-slot connections for adjustably securing them to said posts; a metal block carried by each rod; a set of stator plates carried jointly by said blocks; a set 45 of rotor plates for cooperation with the stator plates; a shaft to which the rotor plates are attached journaled in said cheek plates; an operating member attached to said shaft; and fastening straps secured to 50 the ends of said rods for attaching the instrument to a supporting panel.

4. A variable condenser, according to claim 2, in which the stator plates are carried by two metal blocks; and in which a 55 supporting strap is provided for each block to fasten the same to the adjacent rod, each strap having an adjustable screw-and-slot connection with the respective block.

In testimony whereof I affix my signature.

EDMOND PICARD.
